(57) **CLAIM**

The ornamental design for a vertical garden, as shown and described.

DESCRIPTION

FIG. 1 is a top, front, right perspective view of a vertical garden showing our new design;

FIG. 2 is a bottom, right, rear perspective view thereof;

FIG. 3 is a front side elevation view thereof;

FIG. 4 is a right side elevation view thereof;

FIG. 5 is a rear elevation view thereof;

FIG. 6 is a left side elevation view thereof;

FIG. 7 is a top plan view thereof; and,

FIG. 8 is a bottom plan view thereof.

The broken line shown in the figures is for the purpose of illustrating portions of the vertical garden and forms no part of the claimed design.

1 Claim, 7 Drawing Sheets
